CLAIM

The ornamental design for glove, as shown and described.

DESCRIPTION

FIG. 1 is a top view of the glove embodying the new design;

FIG. 2 is a right side perspective view thereof; and,

FIG. 3 is a left side perspective view thereof.

FIGS. 1-3 show features of a glove in phantom lines. These features are shown for environmental purposes and do not form any part of the claimed design. Further, the phantom lines immediately adjacent the solid-line portions of the design form the boundary of the design, with the phantom lines forming no part of the claimed design.
